Mr. H. H. H.

UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

CONDENSING APPARATUS

Application filed May 28, 1926. Serial No. 112,372.

My invention relates to condensing apparatus and has among its other objects the production of apparatus of the kind described, which is convenient, compact, durable, efficient and satisfactory for use wherever found applicable.

One form of the invention is embodied in a condenser which comprises a casing or housing preferably provided with a removable closure member at one end thereof. Seated in the housing is a unit comprising a plurality of tubular members which communicate with a chamber in one end of the housing and with a chamber formed in the unit. Means is provided for connecting the chamber in the housing with a supply of fluid to be condensed, and means is provided for connecting the chamber formed in the unit with any suitable receptacle or system. The construction is such that a cooling fluid may be circulated through the housing to cool and condense the fluid passing through the members.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a substantially central section taken through a condensing device embodying the invention;

Fig. 2 is a section taken on line 2—2 of Fig. 1; and

Fig. 3 is a section taken on line 3—3 of Fig. 1.

Referring to the drawings wherein I have shown a preferred form of the invention embodied in a condenser, the reference character

10 designates generally a casing or housing which is formed of any suitable material and is preferably substantially rectangular in cross section. The housing 10 is preferably provided with a closure member or cap 11, 50 which is removably secured to the housing by bolts 14, or the equivalents for the purpose. It will be noted that the cap 11 is provided with an aperture 15 into which a pipe 16 is screw-threaded.

Disposed within the housing 10 is a unit 17 comprising a plurality of tubular members 18 formed of relatively thin metal and soldered or otherwise secured to the tubular members 18 are a plurality of fins 20 which are also preferably formed from relatively thin metal. The fins 20 facilitate the exchange of heat from a fluid passing through the tubular members 18 to a fluid circulating around the members 18. The upper ends 65 of the members 18 are preferably soldered or otherwise secured to a plate 22 which has its marginal edges disposed between the housing 10 and its cap 11, suitable packing members 23 being provided at this point, if it is 70 so desired. It will be noted that the bolts 14 pass through suitable apertures formed in the plate 22 and that the tubular members 18 communicate with a chamber 24 formed within the cap 11. The lower ends of the 75 tubular members 18 are preferably soldered or otherwise secured to a plate 25 which forms one wall of a tank 26 communicating with the members 18, the tank 26 being preferably formed with a tubular extension 27 80 which may be screw-threaded at its outer end, as at 28, for a purpose which will presently appear. The tubular extension 27 extends through a stuffing box 28' formed upon the housing 10. This construction compensates for unequal expansion and contraction 85 of the unit 17 and the housing 10 when the device is in operation, the lower wall of the tank 26 being spaced from the lower wall of the housing 10 so that the unit 17 may readi-

ly expand when a heated fluid is passed therethrough. Projecting into the housing 10 are intake and discharge pipes 30 and 31, respectively, which may be connected to 5 my suitable apparatus (not shown) to supply a cooling fluid to the interior of the housing 10. As best shown in Figs. 1 and 2, the housing 10 is preferably provided with a plurality of baffles 32 which insure that the 10 cooling fluid will be brought in contact with all portions of the tubular members 18 and the fins 20. I also prefer to provide reinforcing side members or strips 33 secured to the plate 22, the tank 26 and the fins 20. 15 The operation of my improved condenser is substantially as follows: The device is preferably connected by the pipe 16 to the apparatus (not shown) which supplies the fluid to be condensed and the threaded end 20 of the tubular extension 27 is preferably connected by pipes or the equivalent to a receptacle (not shown) into which the condensed 25 fluid is to be delivered. The cooling fluid is preferably delivered to the housing 10 through the pipe 30 and withdrawn therefrom by the pipe 31. Obviously, there will be an exchange 30 of heat between the fluid being condensed and the cooling fluid and the fluid passing through the tubular members 18 will be condensed.

An advantage of my improved construction is the ease with which the unit 17 may be removed from the housing 10, it being only necessary to remove the cap 11 and then 35 lift the unit from the housing. This facilitates repairs upon the unit 17 and permits the interior of the housing to be cleaned at frequent intervals.

Having thus described my invention, it is 40 obvious that various immaterial modifications may be made in the same without departing from the spirit of my invention; hence I do not wish to be understood as limiting myself to the exact form, construction, 45 arrangement and combination of parts herein shown and described, or uses mentioned.

What I claim as new and desire to secure by Letters Patent is:

1. In a device of the character described, 50 the combination of a member providing a housing, one end of said member being closed except for an aperture provided therein and the opposite end being open, baffles arranged upon opposite sides of the interior of said 55 member and being extended toward each other with the edges thereof arranged relatively to each other to provide a space between them, a unit composed of tubes connected to a plate adapted to be removably 60 arranged in said space between said baffles, a pipe extending from one end of said tubes adapted to be inserted through the aperture in the closed end of said member, said plate 65 forming a closure for the open end of said member, an apertured cap for connection

with said member, and said member having a fluid inlet and outlet.

2. In a device of the character described, the combination of a member providing a housing, said member being closed at one end 70 and having an aperture provided in said end, a fluid inlet and outlet for said member, opposed walls of said member having a plurality of baffles located in relatively different planes upon opposite sides of the interior of 75 said member and providing a passage between them, and a tubular unit adapted to be introduced through the open end of said member and located in the space between said baffles, said unit having a pipe extending 80 from one end thereof adapted to be inserted in the opening in the closed end of said member, and an apertured cap adapted to be removably secured to said member and providing means for holding said tubular unit 85 with relation to said member providing said housing.

3. In a device of the kind described, the combination of a member providing a housing having a closed apertured end and being 90 open at the opposite end, a cap having an opening and providing a closure for said open end, a plate located between said cap and open end of said member, said plate providing a wall between said cap and open end 95 of the housing, tubes extending from said plate, a tank connected with the opposite ends of said tubes, a pipe extending from said tank through the aperture in said end of the housing, baffle plates arranged in relatively different planes and extending in opposite directions interiorly of the housing, fins provided upon said tubes and extending from an edge of one baffle to an edge of another, 100 said baffles and fins providing means for directing circulation of fluid through said housing and said housing having a fluid inlet and outlet.

4. In a device of the character described including a housing for a unit composed of 110 a plurality of tubes adapted to be introduced to and removed from said housing, said housing being closed at one end except for an aperture provided therein and being open at the opposite end, said housing having oppositely 115 extending interiorly arranged ribs having edges thereof arranged relatively to each other to provide a space between them for the reception of said unit, and said housing having a fluid inlet and outlet.

5. In a device of the kind described, the combination of an open ended housing, the opposite end of said housing being closed and said closed end having an aperture, a unit composed of tubes, a plate secured to one end 125 of said tubes and forming a closure for said open end of the housing, a tank secured to the opposite ends of said tubes, a pipe extending from said tank through the aperture in said closed end of said housing, side plates respec- 130

tively arranged at and connecting said first mentioned plate and tank, said side plates, tank and end plate forming a frame surrounding said tubes, a cap removably secured to the open end of the housing and having means for engaging said first mentioned plate, said plate providing means for supporting said unit composed of said plate, tank, tubes and side plates within said housing, said cap having an opening and said housing having inlet and outlet openings.

In testimony whereof, I have hereunto signed my name.

ARTHUR B. MODINE.
